UNITED STATES PATENT OFFICE.

WILLIAM L. SCOTT, OF MONTREAL, QUEBEC, CANADA.

STEAM-BOILER.

1,310,807.

Specification of Letters Patent. Patented July 22, 1919.

Application filed December 4, 1916. Serial No. 135,038.

To all whom it may concern:

Be it known that I, WILLIAM L. SCOTT, a subject of the King of Great Britain, residing in the city of Montreal, Province of Quebec, Dominion of Canada, have invented certain new and useful Improvements in Steam-Boilers; and I do hereby declare that the following is a full, clear, and exact description of the same.

10 My invention relates particularly to locomotive boilers, although it may be applied with advantage to any locomotive-type boiler; and the objects of my invention are, to thoroughly commingle the products of combustion in the fire box before entering the tubes, and to promote the circulation of such products; to present a greater heating surface to the initial action of the fire; to construct a form of fire box readily accessible for repairs and cleaning, and able to resist the stress incident to high steam pressure; to promote the circulation of the water surrounding the heat tubes; and to provide a boiler of the locomotive type in which, without the use of a superheater, the steam will reach the steam-chest or other point of delivery from the boiler at a temperature equal to or greater than that obtained in the boilers of the same type heretofore in use and equipped with superheaters.

My invention may be said briefly to consist of an extension of the tubes of the boiler through the tube sheet into the fire box, with a leg connecting the top of this extension with the top of the boiler and barrel while an extended steam space is formed above the fire box and extending from a short distance in front of the fire box to the rear end of the barrel and preferably equaling in height the top of the cab which permits the entire boiler barrel to be submerged. The advantage of this is that the circulation of the water surrounding the heating tubes is very much improved. The resultant temperature is higher than obtainable in non-submersible boilers, and without a superheater equals or exceeds that obtainable in locomotives or locomotive-type boiler equipped with superheaters. In order to prevent dead spaces within the fire box the extension of the tubes within the same is preferably not applied to the outermost series, which terminate at the tube sheet as usual.

For further comprehension, however, of

my invention reference must be had to the accompanying drawings in which similar reference characters indicate the same parts and wherein;

60 Figure 1 is a side elevation of a locomotive in the main of standard type and with my invention applied thereto;

Fig. 2 is a longitudinal vertical sectional view thereof taken on line 2—2, Fig. 3; 65

Fig. 3 is a horizontal sectional view taken on line 3—3, Fig. 2;

Fig. 4 is a transverse vertical sectional view taken on line 4—4, Fig. 2.

By referring to Fig. 1 it will be seen that the forward position of the boiler and barrel is unchanged from the standard type, but the fire-box portion is raised to present a relatively large steam space *b* in the form of an arc in cross-section, its side lines coinciding with the side lines of the boiler barrel, with the wall of which it is formed as an integral part. The crown sheet *c* of the fire-box is flat and extends forwardly to within a short distance of the forward end of the steam space *b*, thus providing a passage *d* effecting communication between the space within the boiler barrel surrounding the tubes and this steam space *b*. An auxiliary boiler barrel *e* is projected from the usual tube sheet *f* into the fire-box and preferably slightly in rear of a point midway the crown sheet and the rear wall *g* of the fire-box; this auxiliary barrel is preferably circular in cross-section and sufficiently less in diameter than the tube sheet to provide a surrounding space *h* with which the outermost tubes *i* of the boiler connect, while the middle tubes *j* extend continuously through the main and auxiliary barrels. The end *k* of the auxiliary barrel is preferably closed by a tube sheet.

The top of the auxiliary barrel *e* and the crown sheet *c* are connected by a leg *m* extending from the crown sheet substantially to rear end of the auxiliary barrel and effects open connection between the spaces within the latter, the upper portion of the main barrel and the steam space.

Operation.

The heat from the fire in the fire-box is deflected by the auxiliary barrel and the draft of the flues extending therethrough causes the hot gases to cling to the surface 110 of this auxiliary barrel and impart to them a reverberatory action within the fire-box,

thereby effecting a thorough commingling of the air and gases and promoting perfect combustion. The result is that the greatly increased heating surface presented by the auxiliary barrel and the leg connecting the top of it to the steam space enables the augmented heat due to the more perfect combustion, to be absorbed by the water and steam in the barrel and steam space, thus 10 increasing the efficiency of the boiler.

The embodiment of the invention above described, in addition to securing the thorough commingling of the products of combustion and air in the fire-box, promotes the 15 circulation of such products in the fire-box and through the tubes, this being secured by the tubes leading from the space between the auxiliary barrel and the walls of the fire-box. Another advantage being that the particular location and the extent of the steam 20 space *b* promotes the circulation of the water and collecting of the steam.

What I claim is as follows:—

1. In a horizontal tubular boiler, the combination with the barrel, fire box and a steam space above the fire box, of an auxiliary boiler barrel projecting into the fire box, a leg equal in extent to the auxiliary barrel and communicating with the said 25 auxiliary barrel, the main barrel and the steam space above the fire box, the said auxiliary barrel being of less diameter than the main barrel, a series of tubes within the said main barrel and communicating with

the fire box outside of the auxiliary barrel 35 and an inner series of tubes within the said main barrel and extending through the auxiliary barrel and communicating with the fire box at the end of the said auxiliary barrel. 40

2. In a horizontal tubular boiler, the combination with the barrel, a fire box and a steam space above the fire box and greater in extent than the axial length of the fire box with the excess of length protruding 45 forward of the fire box and communicating with the main barrel of the boiler, of an auxiliary boiler barrel projecting into the fire box, a leg equal in extent to the auxiliary barrel and communicating with the said auxiliary barrel, the main barrel and the steam space, the said auxiliary barrel being of less diameter than the main barrel, a series of tubes within the said main barrel and communicating with the fire box outside 50 of the auxiliary barrel and an inner series of tubes within the said main barrel and extending through the said auxiliary barrel and communicating with the fire box at the 55 end of the said auxiliary barrel. 60

In testimony whereof I have signed my name to this specification in the presence of two witnesses.

WILLIAM L. SCOTT.
